CLAIM

We claim the ornamental design for a milling cutter tool, as shown and described.

DESCRIPTION

FIG. 1 is a perspective view of a milling cutter tool in accordance with our design;

FIG. 2 is a top plan view thereof;

FIG. 3 is a front elevational view thereof;

FIG. 4 is a left side elevational view thereof;

FIG. 5 is a rear elevational view thereof;

FIG. 6 is a right side elevational view thereof; and,

FIG. 7 is a bottom plan view thereof.

The broken lines represent portions of the milling cutter tool in which the design is embodied that form no part of the claimed design.
